UNITED STATES PATENT OFFICE.

J. H. KELLER, OF NEW ORLEANS, LOUISIANA.

IMPROVED MACHINE FOR PRESSING SOAP.

Specification forming part of Letters Patent No. 40,627, dated November 17, 1863.

To all whom it may concern:

Be it known that I, J. H. KELLER, of New Orleans, in the parish of Orleans and State of Louisiana, have invented a new and Improved Device for Pressing Soap; and do hereby declare that the following is a full, clear, and exact description of the same, reference being had to the accompanying drawings, making a part of this specification, in which—

Figure 1 is a side sectional view of my invention, taken in the line $x x$, Fig. 2; Fig. 2, a vertical section of the same, taken in the line $y y$, Fig. 1.

Similar letters of reference indicate corresponding parts in the two figures.

This invention relates to a new and improved device for pressing or molding soap; and it consists in the employment or use of a drop, an expanding mold, and a cap-die, all arranged to operate in such a manner as to perform the desired work in a perfect and expeditious manner.

To enable those skilled in the art to fully understand and construct my invention, I will proceed to describe it.

A represents a framing, which may be constructed in any proper manner to support the working parts of the machine; and B represents a drop, which is attached to the lower end of a vertical rack-bar, C, which passes and works freely through a cross-bar, a, at the upper part of the framing A.

D is a horizontal shaft, the bearings b of which are attached to the framing A. This shaft D has a ratchet, c, at one end of it, into which a pawl, d, catches, and at the opposite end of said shaft there is a pinion, e, into which a smaller pinion, f, gears, the latter being on a shaft, g, which has a crank, h, applied to it. On the shaft D there is placed a part pinion, E, or a pinion having a segment or a portion of its teeth removed to form a smooth surface, h', the object of which will be presently shown. The drop B is provided with horizontal arms i, the ends of which are notched to fit on vertical guides j, attached to the inner surfaces of uprights k k of the framing A.

F is a vertical post, which is secured centrally in the lower part of the framing A and in line with the drop B. On the upper end of this post F the mold G is secured. This mold

is of rectangular or other form, having planes l for sides, and said sides are connected by hinges or joints m to the bottom n of the mold, said bottom being firmly attached to the top of the post F. The hinges or joints m admit of the sides l of the mold expanding or extending outward just over the surface of the platform H in the framing A, as indicated in red in Fig. 2.

On the post F there is fitted a slide, I, of the same form as the mold G and post F. This slide I is of such dimensions as to work freely up and down on the post F, and when elevated or raised inclose the mold G and keep its sides l in an upright position in close contact, as shown in both figures. The slide I has a pendent bar, m', attached to two opposite sides of it, and the lower ends of these pendants are connected by a cross-bar, n', which passes through a vertical slot, o, in the post F, and said cross-bar passes through an opening, p, in a lever, J, which passes through the post F, and has a weight, K, on one end of it and a treadle, L, on the opposite end. The weight K has a tendency to keep the slide I elevated and around the mold G, as will be seen by referring to Fig. 2.

M is a cap die of the same form as the mold G, and of such dimensions as to fit snugly over it. This cap-die forms the top of the mold, and is provided with an internal plate, q, which fits into the top of the mold and corresponds with its sides l, as shown in both figures.

The operation is as follows: The operator or attendant raises the drop B by turning the shaft D through the medium of the crank h, the part pinion E raising the rack-bar C in consequence of gearing into the rack. The mold G is then filled with soap, the cap-die M placed on it, and the crank h of the shaft D turned, and the drop B is elevated until the smooth part h' comes opposite the rack, when the drop falls upon the cap-die M and compresses the soap within the mold. The drop B is then elevated sufficiently to admit of the cap-die being removed, and the operator depresses the treadle end of the lever J, and thereby brings down the slide I, which exposes the mold G, so that its sides l will expand or drop outward, to admit of the compressed soap being removed. The operator

then removes his foot from the treadle L, the weight K forces upward the slide I, which again embraces the mold and brings its sides upward in contact, and the mold is ready for a supply of soap for a succeeding operation.

I would remark that the inner surfaces of the sides l of the mold, as well as the under surface of the plate q, may be provided with any device or ornamental configuration or lettering for ornamenting and labeling the cakes or bars of soap.

By this arrangement soap may be compressed into bars or cakes with the greatest

facility and very expeditiously, and at the same time ornamented and labeled.

Having thus described my invention, what I claim as new, and desire to secure by Letters Patent, is—

The drop B, in connection with the expanding mold G, slide I, and cap-die M, all combined and arranged to operate as and for the purpose herein set forth.

J. H. KELLER.
